DESIGN FOR A COMBINATION BOTTLE OR THE LIKE

Basil Sabaneeff, New York, N. Y., assignor, by mesne assignments, to Parfums Chevalier
Garde Inc., a corporation of New York

Application April 22, 1937, Serial No. 68,927

Term of patent 14 years

To all whom it may concern:

Be it known that I, Basil Sabaneeff, a citizen of Russia, and resident of New York, in the county of New York and State of New York, have invented a new, original, and ornamental Design for Combination Bottles or the like, of which the following is a specification, reference being had to the accompanying drawing, forming a part thereof, in which Fig. 1 is a front view of the combination bottle showing my new design; Fig.

2 is a side view; and Fig. 3 is a perspective view
showing the parts of the bottle separated.

I claim:

The ornamental design for a combination bottle or the like, substantially as shown.

BASIL SABANEEFF.
